UNITED STATES PATENT OFFICE

ROSA MAY PICKARD, OF WILMETTE, ILLINOIS

DESIGN FOR A TIE BACK

Application filed September 9, 1929. Serial No. 32,707. Term of patent 7 years.

To all whom it may concern:

Be it known that I, ROSA MAY PICKARD, a citizen of the United States, residing at Wilmette, in the county of Cook and State of Illinois, have invented a new, original, and ornamental Design for Tie Back, of which the following is a specification, reference being had to the accompanying drawing, forming part thereof.

Fig. 1 is a front view showing my new design; and

Fig. 2 is a side view.

I claim:

The ornamental design for a tie back as shown.

ROSA MAY PICKARD.
